R. F. VANCE

FOLDABLE ROCKING CHAIR

Filed Aug. 14, 1926

Patented June 5, 1928.

1,672,437

UNITED STATES PATENT OFFICE.

ROBERT F. VANCE, OF HARDY, ARKANSAS.

FOLDABLE ROCKING-CHAIR.

Application filed August 14, 1926. Serial No. 129,242.

This invention relates to rocking chairs and particularly to foldable rocking chairs and the general object of the invention is to provide a rocking chair which may be folded 5 into very compact form or unfolded to provide a rocking chair of the ordinary form, the chair being so constructed that weight on the seat and pressure on the back will hold the chair in its unfolded condition.

10 A further object is to so form the rear legs and the rockers that the rockers will be provided with abutments against which the lower ends of the rear legs will abut when the chair is unfolded and in use, the rear legs 15 being so constructed as to secure a relatively large bearing surface between the abutments and the legs.

Other objects will appear in the course of the following description.

20 My invention is illustrated in the accompanying drawings wherein:—

Figure 1 is a side elevation of a rocking chair constructed in accordance with my invention;

25 Fig. 2 is a like view to Figure 1 but showing the chair folded;

Fig. 3 is a vertical section of the chair unfolded or opened;

30 Fig. 4 is a fragmentary sectional view showing the manner in which the legs rest or abut against the abutments of the rockers;

Fig. 5 is a section on the line 5—5 of Figure 4.

Referring to these drawings it will be seen 35 that I have provided the rockers 10. These rockers have the usual form but inward of the rear ends of the rockers are provided with upwardly extending protuberant portions or abutments 11. The upper faces of these abutments are provided with the wear plates 12. The seat, which is designated 40 generally 13, has a seat frame including side members 14, the forward ends of which are provided with downwardly projecting ears 15, and between these ears with a transversely extending bar 16. The rear ends of the side members 14 have upwardly extending lugs 17.

The front legs 18 have their upper ends 50 disposed between the ends of the bar 16 and the lugs or ears 15 and the lower ends of these legs being bolted or otherwise attached to the downwardly extending metallic straps 19 which embrace the forward ends of the 55 rockers and are bolted or otherwise pivotally engaged therewith by bolts 20.

The forward legs may be connected by the usual round 21. The back includes the downwardly extending side members 22 which are overlapped by the ears 17 and 60 pivoted to these ears by transversely extending pins or equivalent members 23. The seat frame includes a transverse cross bar 24, through which a seat pin or pins 23 pass.

Attached to the lower end of each leg 22 65 is a pair of straps or irons 25 which extend down below the lower end of the member 22, which members constitute legs integral with or rigidly engaged with the back frame, and these irons or straps 25 are bolted or otherwise pivotally engaged with the rockers 10 at a point below the forward ends of the 70 abutments 11. The lower end 26 of each leg is disposed rearward of the pivot 27 for the 75 leg and thus when the back of the chair extends rearward at a slight angle to the vertical, the lower ends 26 of the legs will bear against the wear plates 12 and this will limit the rearward movement or rearward inclination of the back and rear legs 80 so that the back cannot turn backward any further than it is permitted to do by the stops constituted by the abutments and the wear plates. It will be obvious that if the 85 legs are disposed at their lower ends in line with the pivotal connection, the lower ends of the legs would not abut solidly against the abutments but there would be merely a wedging action which would tend to prevent the folding up of the chair and tend to break 90 off or wear the lower ends of the legs.

The back frame may have a canvas web 28 attached thereto or any other form of back cushion or web may be used and while I have illustrated the seat of the chair as 95 being formed of a metal sheet 29 attached to the frame of the seat, I do not wish to be limited to this as any other form of seat bottom might be used. Of course, I do not wish to be limited to the exact form of the 100 seat frame or the back frame or the minor details of construction except as defined in the appended claim.

I claim:—

A folding rocking chair of the character 105 described including rockers, a seat, forward legs pivotally engaged with the forward end of said seat, means pivotally engaging the legs with the forward ends of the rockers, said means permitting the forward legs to 110 turn into a position of approximate alignment with the forward end portions of the

rockers, a back having legs rigid throughout their entire extent and to which the rear end of the seat is pivotally connected, straps rigidly attached to the lower end of each rear leg and pivotally engaged with the rockers, the rockers having abutments with which the lower ends of the rear legs engage when the chair is fully extended, said abut-

ments preventing the rearward turning movement of the legs on the rockers but ¹⁰ permitting downward and forward turning movement of the rear legs on the rockers.

In testimony whereof I hereunto affix my signature.

ROBERT F. VANCE.
